UNITED STATES PATENT OFFICE.

DAVID S. BOYLES, OF ROCK HILL, SOUTH CAROLINA.

CLOTHESPIN.

1,426,251.

Specification of Letters Patent. Patented Aug. 15, 1922.

Application filed June 25, 1921. Serial No. 480,474.

To all whom it may concern:

Be it known that I, DAVID S. BOYLES, a citizen of the United States, resident of Rock Hill, in the county of York and State 5 of South Carolina, have made a certain new and useful Invention in Clothespins; and I declare the following to be a full, clear, and exact description of the same, such as will enable others skilled in the art to which 10 it appertains to make and use the invention, reference being had to the accompanying drawings, and to letters or figures of reference marked thereon, which form a part of this specification.

15 Figure 1 is a face view of the invention, as applied.

Figure 2 is a perspective view of the invention.

Figure 3 is an edge view of the same.

20 The invention has relation to clothes pins, having for an object to provide an improved spring wire clothes pin, and the invention consists in the novel construction and combinations of parts, as hereinafter set forth.

25 In the accompanying drawings illustrating the invention, the numeral 2 designates the clothes line, whereon is constantly engaged the clothes pin 3, composed of a single piece of strong spring wire, the free ends 30 3' of which project above the line 2 in converging relation to form a handle loop 4, said ends terminating in eyes 5, engaging each other. Each of the end portions 3' extend first downwardly below the line 2 and

35 thence upwardly to form a loop 6, the two loops 6 being located upon opposite sides of the line 2, the upwardly bent ends of each loop being coiled at 7 laterally towards and to position directly over the line 2, the coils 40 7 resting upon said line or being adapted to rest thereon, the other end of each coil being then bent downwardly and upwardly to form a loop 8 matching and laterally opposite to the loop 6, the former loops being

45 also located upon opposite sides of the line 2, the wire forming the loop 8 being bent into S form, or each loop 8 being double, the inner terminals thereof extending downwardly to form a loop 9 extending downwardly below 50 the loops 6 and 8 to a considerable extent.

The S form or double loops 8 have their upper portions laterally opposite and normally engaging the line 2 and provide an extended bearing surface for engagement 55 with the clothes hung upon the line, each loop 8 being in the plane of the larger loop

9; and each loop 6 being bent laterally outwardly at its lower end at 6' to facilitate engagement with the clothes being hung on the line. 60

The upper handle loop being grasped with one hand, the clothes pin may be raised from its normal position wherein the two coils 7 rest on the line, to a position shown in Figure 1 of the drawings, the loop 9 limiting the movement of the clothes pin upwardly by engagement with the line 2 which passes therethrough. The clothes may then be engaged with the line, and the pin then lowered to engage the spring loops 6 and 8 with the 65 clothes on the line, the coils 7 limiting the downward movement of the pin as stated. 70

In the raised position of the pin the loops 6 and 8 are raised sufficiently above the line 2 to admit of the clothes being readily engaged with said line thereunder. 75

The coils 7 have the function of limiting the downward movement of the pin, and of strengthening the lateral spring action of the loops 6 and 8, the S form loops 8 further 80 strengthening the lateral spring action thereof.

The free ends of the wire being always above the clothes, can never engage the same, whereby any liability or tendency to tear 85 the clothes is avoided.

The device when raised has no binding engagement with the line and may be moved from place to place along the line with ease.

I claim:—

1. In a spring wire clothes pin, a wire gripping member including a coil in the general plane of the clothes line and adapted to rest thereon to limit the downward movement of the pin, the ends of said coil having laterally opposite loops depending therefrom and straddling said line and extending below the same and adapted to pin the clothes to the line. 95

2. In a spring wire clothes pin, a wire gripping member including a coil in the general plane of the clothes line and adapted to rest thereon to limit the downward movement of the pin, the ends of said coil having laterally opposite loops depending therefrom and straddling said line and extending below the same and adapted to pin the clothes to the line, one of said loops being of S-form. 105

3. In a spring wire clothes pin, two wire gripping members including each a coil in the general plane of the clothes line and

adapted to rest thereon to limit the downward movement of the pin, the ends of said coil having laterally opposite loops depending therefrom and straddling the said line and extending below the same and adapted to pin the clothes to the line, the upper ends of certain of the loops of the wire gripping members at opposite sides of the line being extended upwardly and joined to form a handle loop above the clothes line, and the upper ends of the other loops of said mem-

bers at opposite sides of the line being extended downwardly and joined to form a lower loop below the line, said lower loop and said handle loop both crossing the line above and below the same. 15

In testimony whereof I affix my signature in presence of two witnesses.

DAVID S. BOYLES.
